No. 851,162.

PATENTED APR. 23, 1907.

W. H. COE.

MEANS FOR FEEDING METALLIC LEAF TO A STAMPING PRESS.

APPLICATION FILED JUNE 29, 1905. RENEWED MAR. 11, 1907.

UNITED STATES PATENT OFFICE.

WALTER H. COE, OF PROVIDENCE, RHODE ISLAND.

MEANS FOR FEEDING METALLIC LEAF TO A STAMPING-PRESS.

No. 851,162.

Specification of Letters Patent.

Patented April 23, 1907.

Application filed June 29, 1905. Renewed March 11, 1907. Serial No. 361,782.

To all whom it may concern:

Be it known that I, WALTER H. COE, a citizen of the United States, and a resident of Providence, in the State of Rhode Island, have invented a new and useful Improvement in Means for Feeding Metallic Leaf to a Stamping-Press, of which the following is a specification.

My invention consists in the improved means for feeding metallic leaf to the stamping die in suitably divided lengths, from a package-roll in which the metallic leaf is spirally wound with a paper strip.

In the accompanying drawings:—Figure 1 represents a side view of the required moving parts, which are shown without the frame, for feeding metallic leaf from a package-roll to a stamping die, the metallic leaf being indicated by means of the dotted line. Fig. 2 represents the top view of the same. Fig. 3 represents an end view. Fig. 4 represents an axial section of the heating roll. Fig. 5 represents an enlarged vertical section taken through the cutter-holding carriage in the line of the axis of the cutter.

In the drawing, *a* represents the plunger of the stamping press, *b* the die, and *c* the gas tube, by means of which the die *b* is to be heated, and *d* the platen upon which the book cover *e*, or other article, is to be placed for receiving the impression of the die. Upon the cranked driving-shaft *f*, are placed the grooved wheels *g* *g*, which are made adjustable along the said shaft by means of their tightening screws *h*, and upon the parallel shaft *f*', are placed the similarly adjustable grooved wheels *g*' *g*', and in the peripheral grooves of the said wheels are placed the narrow bands *i* *i*, which act as carriers for the metallic leaf, the wheels *g* *g*' and the shaft *f*', to which they are attached, being driven by the action thereon of the said bands. Upon the shaft *f*' is placed the gear wheel *j*, which engages with the gear *j*' upon the projecting hollow shaft of the heating roll *k*, within the cavity of which is placed the gas pipe *l*, whereby the periphery of the roll *k* may be suitably heated to cause the loosening of the metallic leaf from the paper strip *p*. The wheels *g* *g* and the heating roll *k*, are so arranged that the bands *i* *i*, will be pressed lightly against the periphery of the said roll *k*, and the gears *j* and *j*' are to be so proportioned that the surface speed of the said roll *k* and of the said bands will be equal.

Upon the fixed parallel guide rods *a* *a*' is

placed the sliding carriage *m*, upon which is held the loose circular cutter *n*, by means of which the metallic leaf which has been unwound from the package-roll *o* may be severed into the desired lengths through the action of the peripheral edge of the said cutter upon the metallic leaf and the paper strip *p*, when they are supported by the periphery of the roll *k*, as shown in Fig. 1, the cutter *n* being mounted for action upon a sliding block *q*, which is pressed forward to sever the metallic leaf by means of a spring *r*, as shown in Fig. 5. The sliding carriage *m* is to be pulled in one direction by means of a suitable spring *s*, or an equivalent weight, and in the opposite direction by means of the cord *t*, which is attached at one end to the carriage *m*, thence passing around the loose idler pulleys *u* *u*, to attachment to the end of the pedal lever *v*, so that a downward movement of the foot of the operator upon the said pedal lever, will cause the forward movement of the cutter along the periphery of the roll *k*, to the opposite end of the said roll, and then the action of the spring *s* will carry the cutter back in the same track so as to completely sever the metallic leaf upon the paper strip *p*, the cutter at its backward position passing from its pressure against the periphery of the roll *k*, to a resting position against the side of a stationary guide *w*, arranged in line with the said periphery. At the under side of the bands *i* *i*, and in contact therewith, is placed a body of wax *z*, or some substance adapted to cause the adhesion of the edges of the severed sheets of metallic leaf to the said bands, and at the back of the wheels *g* *g*', and the bands *i* *i*, is placed the brush *z*, which serves to remove any scraps of metallic leaf which may be adherent to the said bands subsequent to the action of the stamping die.

In operating the machine, the stamping die *b* is to be brought down upon the book cover *e*, by means of the right hand of the operator, and while resting upon the said cover the cutter *n* is to be operated by means of the pedal lever *v*, to sever the fillet of metallic leaf upon the paper strip *p*, then upon raising the die from the cover, the carrying bands *i* *i* are to be brought forward to the proper distance by turning the crank *y* with the left hand of the operator, then the die *b* is to be brought down upon another cover *e*, and the cutter *n* operated as before, and these movements are to be continuously repeated, the metallic leaf upon the paper strip being thus

severed into the proper lengths suitable for the dimensions of the die, and by the employment of the severed sections of metallic leaf instead of a continuous fillet, imperfect action and waste of the metallic leaf is avoided.

I claim as my invention:—

1. In an apparatus for feeding metallic leaf to a stamping press from a package roll, the combination of the die-holding plunger, and the platen, with the parallel endless bands for supporting the edges of the sheets of metallic leaf, means for depositing the sheets of metallic leaf thereon from the package roll, and means for imparting movement to the said bands to carry the metallic leaf between the die-holding plunger and the platen.

2. The combination of the die-holding plunger, and the platen, with the bands for supporting the edges of the sheets of metallic leaf deposited thereon, means for imparting movement to the said bands, and means for applying an adhesive material to the bands.

3. The combination of the die-holding plunger, and the platen, with the bands for supporting the edges of the sheets of metallic leaf deposited thereon, means for applying adhesive material to the said bands, and means for removing the adhering metallic leaf from the bands.

4. In an apparatus of the character described, the combination of the die-holding plunger, the platen, the parallel endless bands for supporting the edges of the me-

talic leaf at opposite sides of the die, and means for imparting movement to the said bands, with the heating roll adapted to hold the metallic leaf against the said bands for attachment thereto.

5. In an apparatus of the character described, the combination of the die-holding plunger, the platen, the parallel endless bands for supporting the edges of the metallic leaf at opposite sides of the die, and means for imparting movement to the said bands, with the heating roll adapted to hold the metallic leaf against the said bands for attachment thereto, and a cutter for dividing the fillet of metallic leaf into suitable lengths preparatory to its attachment to the supporting bands.

6. In an apparatus of the character described, the combination of the die-holding plunger, the platen, the parallel endless bands for supporting the edges of the metallic leaf at opposite sides of the die, and means for imparting movement to the said bands, with a roll adapted to hold the metallic leaf against the said bands for attachment thereto, and a cutter bearing against the periphery of the said roll for dividing the fillet of metallic leaf into suitable lengths, preparatory to its attachment to the supporting bands, and means for reciprocating the said cutter.

WALTER H. COE.
